UNITED STATES PATENT OFFICE.

PAUL H. HORWITT, OF BROOKLYN, NEW YORK, ASSIGNOR TO INDEPENDENT PAPER MILLS, INC., OF BROOKLYN, NEW YORK.

DISPENSER.

Application filed March 23, 1926. Serial No. 96,894.

This invention relates to containers for use in connection with folded paper napkins as extensively used in public eating places, and has as one of its objects to provide a portable container capable of being moved about upon the surface of a dining table or wholly removed therefrom at will.

Another purpose is to produce a neat appearing napkin holder out of which napkins may be withdrawn from either of its two delivery sides, rendering it unusually convenient.

A further feature is in the provision of means for pressing the napkins on both sides uniformly into an easily accessible position.

Other aims are in providing means for locking the parts of the holder to avoid pilfering and waste, and further, in the production of an inexpensive holder which may well be considered as an ornamental adjunct to a dining table.

These several objects are fully attained by the novel design, and construction of parts herein disclosed and illustrated in the drawings constituting a component hereof, and in which:—

Fig. 1 is a front elevational view of a napkin holder made in accordance with the invention.

Fig. 2 is a vertical sectional view taken substantially on the center line of Fig. 1.

Fig. 3 is a transverse sectional view taken on line 3—3 of Fig. 2.

Fig. 4 is an enlarged fragmentary sectional view of the lower corner of the holder.

As will be seen in the drawing the entire structure is composed almost wholly of sheet metal and consists of two similar hollow drawn casings, having faces 10 and 11 curved at their edges into sides 12 and 13 and ends 14 and 15.

The side and end walls 13 and 15 are disposed in level planes which extend to the medium line of the structure, but the opposite side and end walls 12 and 14 are offset outwardly at their edges and extended circumambiently to enclose the edges of the mating member by flange elements 16.

The normal position of these casings, which are oblong rectangles in shape, is vertical and they are connected at their bottoms by a hinge, one member 17 of which is spot welded or otherwise permanently secured to the lower flange 16.

The outer edge of the hinge member 17 is

curled to engage a pin 18 connecting a similar curled member 19 formed on the edge of a strip 20, bent lengthwise at a right angle, passed through an appropriate opening in the lower wall 15 of the mating casing member, and permanently secured to the inner side of the wall, as best seen in Fig. 2.

At the top of the casing an angular detent 21 is fixed to the inner surface of the wall 15, its smaller bevelled end being adjacent the edge of the casing, and secured to the wall 14, opposite the detent, is a spring catch 22 shaped to engage the detent when the casings are pressed together, thus, in conjunction with the hinge, normally preventing separation.

However, in order to provide for opening the holder on its hinge, a small aperture 23 is formed through the end wall 14 to align with the catch 22 and by the insertion of a suitable wire or the like the catch may be pressed inwardly to release the detent.

Formed in the faces 10 and 11 are elongated rectangular openings 24 and 25 having recessed corners, the edges of the openings being preferably curved outwardly to a slight extent and smoothly finished to avoid scratching or cutting a person's fingers in removing the outermost of a stack of napkins X, held against the inner surface of the plates 10 and 11.

Such pressure is produced by a pair of bowed spring arms 26 their lower ends being riveted to a flat cross bar 27 extending between the side walls 13 and having pintles 28 on its ends to engage in openings in the side walls, as best seen in Fig. 4.

From the foregoing it will be seen that the spring arms 26, which contact with the innermost napkin in each side of the holder at approximately the center of the openings 24 and 25, act with entire uniformity, due to their pivoted support and quite irrespective of inequalities in the thickness of the stock of napkins in the opposed casing sides.

Preferably the holder is raised from a table by feet 29, a pair of which are secured to the lower end walls of each casing member near their faces, these feet, spherical or otherwise, preventing scratching or marring the table surface and also clearing the case thereof so as to admit separation of the casing sides when replenishing its contents.

Obviously filling is easily accomplished by depressing the spring catch 22, opening the

sides by turning them outwardly on the hinge and swinging the spring arms 26 to one side while filling a supply of napkins into the other side.

5. When this has been done and both sides filled, the casing sides are brought together, the spring catch gliding over the detent until it has passed into engaging position.

It is to be noted that the holder is substantially dust proof, as the outermost napkins are held against the faces, covering the openings therein, while all other openings and joints are protected from the intrusion of matter.

10. As changes of construction could be made within the scope of the invention, it is intended that all matter contained in the foregoing description or shown in the accompanying drawings shall be interpreted as 20 illustrative and not in a limiting sense.

Having thus described my invention, what I claim as new and desire to secure by Letters Patent, is:—

1. In a dispenser for napkins and the like, 25 the combination with receptacles hingedly connected together at one end and provided with openings for the withdrawal of the contents thereof, of means for adjustably positioning the said contents adjacent the said 30 openings and comprising spring members hingedly mounted at one end on said receptacles and adapted with their free ends to press the said napkins toward the said open-

ings and means for locking together the free ends of the said hinged receptacles.

2. In a dispenser for napkins and the like, the combination with receptacles hingedly connected together at one end and provided with openings for the withdrawal of the contents thereof, a cross bar extending between the side walls of the receptacle and having 40 pintles on its ends to engage an opening in the side walls, a pair of flat bowed spring arms having their lower ends riveted to the cross bar and adjustably positioning the said 45 contents adjacent the said openings and adapted with their free ends to press the napkins towards the said openings.

3. In a dispenser for napkins and the like, the combination with receptacles hingedly connected together at one end and provided with openings for the withdrawal of the contents thereof, of means for adjustably positioning the said contents adjacent the said 50 openings and comprising spring members hingedly mounted at one end on said receptacles and adapted with their free ends to press the said napkins toward the said openings, a spring catch mounted on one of the 55 receptacles and shaped to engage a detent on the other receptacle for locking together the free ends of the said hinged receptacles, and an aperture through the wall of receptacle to permit the insertion of a tool to disengage the spring from the detent.

PAUL H. HORWITT.
